TAP-CHANGING INTERLOCK

Application filed May 27, 1926. Serial No. 112,096.

Our invention relates to electric tap-changing devices and particularly to an interlocking device between a motor operating mechanism and a manually operating mechanism.

One object of our invention is to provide an interlocking device between the manual and the motor operating mechanisms for a tap-changing device that shall preclude the 10 operation of the motor driving mechanism while the manual operating mechanism is connected.

Another object of our invention is to provide an interlock between the motor driving 15 mechanism and the manual operating mechanism of a tap-changing device such that the engagement of the manual operating mechanism with the main shaft shall automatically release a motor brake.

20 A further object of our invention is to provide an indicating and stop device for a tap-changing device that shall be brought into operation when the manual operating mechanism is brought into engagement with the main driving shaft.

25 Tap-changing devices are usually designed for selective motor or manual drives. When the tap-changing device is motor driven, a system of pilot switches controls the operation of the motor so that the tap-changing mechanism moves but a single step in response to each energization of the motor. However, when such devices are manually driven it becomes essential that some means

30 be provided to prevent over travel of the device when it is in operation, and, at the same time, to prevent the possibility of the motor driving mechanism becoming energized.

35 Accordingly, we have designed an interlocking mechanism that is actuated simultaneously with the engagement of the manual driving mechanism with the main driving shaft. This interlocking mechanism serves to release the brake on the motor, disconnect the 40 motor from its supply circuit and to bring into operation an indicating and stop mechanism for the tap-changing device.

45 The single figure of the accompanying drawing is a diagrammatic view of circuits and apparatus embodying our invention.

Our invention comprises in general a main driving shaft 1 that may be selectively driven by a motor 2 or a manual operating mechanism 3, and an interlocking device 4 that connects the motor and the manual driving 55 mechanisms.

The motor 2 is connected by a shaft 5 to a worm-wheel 6 that, in turn, drives a reducing gear 7, mounted on the shaft 1. A brake band 8 is supported between a support 9 and 60 a resilient mounting 10 for engagement with a hub 12 mounted on the shaft 5. An electromagnet 11 is provided for releasing the brake band 8 when the motor 2 is energized.

A fitting 13 is mounted at one end of the 65 shaft 5 and is provided with a square seat 14 for the reception of a key 15 mounted at one end of a shaft 16. A hand wheel 17 is mounted at the other end of the shaft 16. Engagement between the key 15 and the seat 70 14 is made by turning the shaft 16 about an axis 18.

The axis 18 is connected to the shaft 16 by a lever 19, the outer end of which extends downwardly and outwardly as at 21 75 to engage a suitable locking device 22. A pointer 23 is attached to the lever 19 for cooperating with an index 24 having the legends "Hand" and "Motor" printed thereon. Accordingly, the position of the pointer 23 80 relative to the index 24 apprises the operator whether the shaft 5 is in condition to be driven by the motor 2 or the manual driving mechanism 3.

85 A coil spring 25 is mounted at the inner end of the lever 19 to assist the operator in moving the shaft 16 inwardly, or to the left of the figure and to assist in operating the interlock 4 as hereinafter described. A lever 26 is pivotally connected to the inner end of 90 the lever 19 and is fixedly connected to a shaft 27 that in turn is connected through a bevel gear train 28 for actuating a shaft 29.

95 The shaft 29 of interlock 4 is, accordingly, directly connected to the shaft 16 of the hand driving mechanism 3. The other end of the shaft is connected by an arm 30 and the link 31 to a switch 32 connected in one of the conductors of a supply circuit 33 for the motor 2. The link 31 also actuates a bell crank 100

34 that operates the resilient mounting 10 for the brake band 8.

The main shaft 1 supports a wheel or positioning device 36 that is provided with a series of notches 37 in the outer face thereof. Outwardly beyond the wheel 36, a plurality of cams 38 are mounted on the shaft 1 for controlling a plurality of circuit interrupters 39 constituting elements of a tap changing device. Within the projection of the wheel 36, a bracket 41 is fixedly mounted on the shaft 29, a second bracket 42 is loosely mounted on the shaft 29 outside of the bracket 41 and terminates in an arm 43 that is adapted to fit into the notches 37 of the wheel 36. Springs 44 constitute a resilient connection between the brackets 41 and 42 whereby the latter is biased into a downward position to either engage the bracket 41 or the wheel 36, 20 in a manner hereinafter described.

In practice, a plurality of pilot switches associated with the cams 38 and circuit interrupter 39 also control the motor 2, but as such pilot switches constitute no part of the present invention, and for the sake of simplifying the showing of the present invention, they have been omitted.

For the motor operation of the shaft 1, the manual operating mechanism 3 is disconnected from the shaft 5 and the interlock 4 is in the relative position shown in the drawing. Under such conditions, the motor 2 rotates thereby causing the cams 38 to alternately open and close the circuit interrupters 39 thereby to control the tap connections of a transformer, not shown.

For the manual operation of the tap-changing device, the shaft 16 is forced inwardly to cause engagement of the key 15 in the seat 14 and at the same time to impart a counter-clock movement to the shaft 27 which movement is transmitted through the gear 28 to the shaft 29. The shaft 29 is given a turning movement that lowers the bracket 41, the arm 30 and the link 31 with the result that the arm 43 is brought to bear on the face of the wheel 36, the switch 32 is opened and the brake band 8 is loosened on the hub 12. As previously explained, the opening of switch 32 prevents the operation of the motor 2, and the loosening of the brake band 8 permits the shaft 5 and the attached motor 2 to be turned without prohibitive exertion on the part of the operator.

With the parts thus connected, the hand wheel 17 is turned in either direction to cause the desired sequence of operation of the cams 38. The notches 37 are spaced about the periphery of the wheel 36 in such manner that they correspond to the various positions of the cams 38. Accordingly, when the shaft 1 is turned far enough to cause the cams 38 to operate the desired circuit interrupter 39, the arm 43 will drop into one end of the notches 37 and prevent further movement of

the shaft 1. The co-operation of the arm 43 and the notches 37 serves to give an indication of the position of the shaft 1 and also to act as a stop for movement of that shaft. In order to move the tap changer another stage, it is necessary for the operator to lift the handle 43 out of a notch 37, after which it will pass along the face of the wheel 36 until the next notch 37 is engaged thereby indicating the completion of another tap change.

When the manual operating mechanism 3 is removed from engagement with the shaft 5, the shaft 29 is moved to raise the bracket 41 far enough to permit the arm 43 to clear the periphery of the wheel 36 at the same time the switch 32 is closed and the brake band 8 again tensioned.

It will thus be seen that we have devised an interlock between a motor driving mechanism and a manual operating mechanism for a shaft such that when the manual driving mechanism is brought into operation it opens a switch controlling the supply circuit to the motor, releases the motor brake and brings into operation an indicating and stop mechanism for the shaft.

It is to be understood that such changes may be made in the size, disposition and connections of the component parts of our invention, as shall fall within the scope of the appended claims.

We claim as our invention:

1. The combination with a shaft, a driving motor therefor and a brake for the motor, of manual means for operating the shaft comprising means for releasing the brake.

2. The combination with a shaft, a driving motor therefor, a supply circuit and a brake for the motor, of manual means for operating the shaft comprising means for releasing the brake and for disconnecting the motor from its supply circuit.

3. The combination with a shaft and a driving motor therefor, of manual means for operating the shaft and a positioning device for the shaft rendered operative by the manipulation of the manual operating means.

4. The combination with a shaft and a driving motor therefor, of manual means for operating the shaft, and a positioning device for the shaft rendered operative upon the engagement of the shaft by the manual operating means.

5. The combination with a shaft, a driving motor, a brake, a switch for the motor and a detachable manual operating means for the shaft, of an arm actuated upon the engagement of the shaft with the manual operating means for controlling the switch and brake.

6. The combination with a shaft, a driving motor, a brake, a switch for the motor and a detachable manual operating means for the shaft, of an arm actuated by the engagement of the shaft with the manual op-

erating means, for controlling the switch, the brake, and a position indicating and stop means associated with the shaft.

7. The combination with a shaft, a notched wheel carried thereby and a detachable operating mechanism, of a stop mechanism brought into engagement with the notched wheel during the connection of the detachable operating mechanism to the shaft.

10 8. The combination with a shaft and a notched wheel carried thereby, of an indicating and stop mechanism comprising a second shaft and an arm yieldingly supported by said second shaft to be turned into engagement with said notched wheel.

15 9. The combination with a shaft and a notched wheel carried thereby, of an indicating and stop mechanism comprising a second shaft, a bracket fixedly attached to the second shaft, a second bracket loosely mounted thereon, a resilient connection between the brackets and an arm mounted on one of the brackets whereby upon the turning of the second shaft the arm is brought into 25 yielding engagement with the notched wheel.

In testimony whereof, we have hereunto subscribed our names this 14th day of April, 1926.

LELAND H. HILL.
